UNITED STATES PATENT OFFICE

2,669,300

CERAMIC DISTRIBUTOR FOR RADIANT GAS BURNERS

Emil Blaha, Cheltenham, Pa., assignor to Selas Corporation of America, Philadelphia, Pa., a corporation of Pennsylvania

Application March 11, 1950, Serial No. 149,086

10 Claims. (Cl. 158—116)

1

The present invention relates to gas burners, and more particularly to distributors used with radiant cup type gas burners.

The distributor of the present invention is particularly adapted to be used with radiant cup burners of the type described and illustrated in Hess Patent 2,215,079 granted on September 17, 1940, although it can be used with other types of burners. The distributors illustrated in the above-mentioned patent are relatively complicated ceramic moldings of one piece construction. Those distributors are characterized by a head portion having a threaded stem projecting from one side thereof. A plurality of slots are formed in the sides of the stem, and terminate at the periphery of the head portion. The stem is threaded into an opening in the base of a cup formed in a ceramic block. The slots on the stem of the distributor form passages through which the mixture flows into the cup to be burned as it leaves the slots at the periphery of the head. Distributors of the type mentioned are difficult to manufacture because the threads on the stem are interrupted at a number of points by the slots passing up the side thereof. Furthermore, the capacity of a given size burner, or the volume of combustible mixture that can be supplied through the slots, is limited by the width of the slots. The slots cannot be made very wide since they reduce the effective length of the threads that are used to hold the distributor in place. Another difficulty with distributors of the type mentioned is that small pieces of ceramic may become lodged in the slots to clog up the same and make insertion and removal of the distributors difficult.

The distributor of the present invention overcomes the drawbacks of the distributors previously used in several respects. The present distributor comprises two or more assembled parts, depending upon its capacity and size. In the construction disclosed herein the distributor is so formed that the threads on the stem are continuous. Ports through which the fuel mixture flows are located within the stem, and are of an area larger than can be obtained by the use of slots; so that the capacity of the burner is increased.

It is an object of the invention to provide a distributor for use in gas burners that has a large capacity for a given size. It is a further object of the invention to provide a gas burner distributor which is easily inserted and removed from the burner.

Another object of the invention is to provide a distributor which is easy to manufacture and

2

assemble. Even though two dies are required, instead of the one now used for distributor manufacture, the dies are simple in design and inexpensive. Furthermore, the manufacture of distributors as disclosed herein may be performed by inexperienced or unskilled labor, whereas present manufacture requires the use of skilled workmen.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described a preferred embodiment of the invention.

Referring to the drawing—

Figure 1 shows a view in section of an assembled burner;

Figure 2 is an enlarged view of a distributor for use in the burner;

Figure 3 is a view taken on line 3—3 of Figure 2;

Figure 4 is a sectional view of a modified form of distributor;

Figure 5 is a view of another modified form of the distributor;

Figure 6 is a view taken on line 6—6 of Figure 5; and

Figure 7 is a view of a still further form of the invention.

Burners of the type with which the present invention is concerned may be used in almost every type of furnace. These burners are placed within the walls, floor or roof of a furnace so that the radiant heat developed thereby will be projected into the furnace chamber and against work that is being heated. For purposes of description it will be assumed that the burner is located in the wall of a furnace and forms a part thereof.

The burners are mounted in and form a part of the side walls 11 of a furnace chamber. As shown most clearly in Figure 1, each burner comprises a molded block 21 of ceramic material which is secured in position in the wall 11 by a suitable high temperature firebrick cement 22. The block 21 may have different portions thereof formed of refractory materials possessing different heat resisting and thermal conducting properties, so that each portion will possess the most desirable heat resisting and thermal properties for its particular position in the block. The different portions of each block are com-

pacted into a single unitary structure by a suitable molding operation to provide block 21 which is rectangular in cross-section.

Block 21 is formed with a central passage 23 which extends therethrough and terminates at 8 cup-shaped space 24 formed at the inner face of the side wall 11. Within the passage 23 is disposed a burner tube or sleeve 25 having the inner end thereof terminating at a region closely adjacent to the inner end of the passage 23. The 10 outer portion of tube 25 is formed with an outwardly extending shoulder 26 which fits snugly against a collar 27. The collar 27 may be a pre-formed and pre-fired body of porcelain which is thereafter united to the block 21 at the same time 15 that the different portions of a block are united together by a firing operation. In order to position tube 25 accurately in the passage 23, the 20 surface of the collar 27 engaged by the shoulder 26 may be ground after the block 21 is formed. The shoulder 26 of tube 25 is positioned in an 25 enlarged opening or well 28 extending from the outer end of passage 23 to the outer face of the side wall 11. Within the outer end of burner tube 25 is secured the inner end of a metal tube 29, as by cement, for example.

The outer end of metal tube 29 is secured to the inner end of a short length of flexible tubing 39 which is fastened at its opposite end to the inner end of an internally threaded opening 31 formed in a hollow cover plate 32. Within the hollow cover plate 32 is provided a helical coil spring 33 which is arranged to exert force against the outer end 34 of shoulder 26. In this way the shoulder 26 will always snugly press against the collar 27 irrespective of the relative expansion of the different burner parts over the wide temperature range encountered during operation. The cover plate 32 is sufficiently large to close the enlarged opening or well 28 and is secured at 35 to an outer metallic shell 36 of the furnace wall 11.

A suitable combustible mixture is delivered from a source of supply through conduit 37 connected to the internally threaded opening 31 of the burner. The conduit 37 for supplying combustible gas mixture to the burner may be arranged in any desirable manner, and suitable controls may be provided to adjust the pressure and the rate at which the combustible gas mixture is supplied to the burner. The combustible gas mixture passes through the short length of flexible tubing 38 and metal tube 29 into the burner tube 25.

The inner end of tube 25 is threaded to receive a distributor which serves the purpose of breaking up the stream of combustible fuel mixture supplied to the tube into a plurality of small jets or flames so that the fuel will be burned in a plurality of jets along the surface of the cup. The distributor is shown in place in the burner in Figure 1 and on a larger scale in Figures 2 and 3. The distributor is made of a ceramic material and comprises a cylindrical head 38 that has a cylindrical stem 39 extending from one face thereof. The lower surface of the head has a number of fins 41 extending perpendicularly thereto and in a substantially radial direction. These fins form between them a plurality of slots 42 through which the combustible mixture is discharged into the cup. As is best shown in Figure 2, the fins extend inwardly from the outer surface of the head to a point spaced from the stem 39. The space between the inner edges of the fins and the surface of the stem forms an

annular passage or channel 43 that is in communication with each of the slots. It will be seen that the top and bottom edges of the fins are not perpendicular to the axis of head 39 and stem 39, but are at such an angle thereto that they extend substantially parallel to the surface of cup 24 of the burner block.

The stem 39 receives a cylindrical member 44 that is located thereon by engagement between the upper surface of this member and a shoulder 45 formed on the stem. As best shown in the drawings, the lower end of the stem is of a reduced diameter so that a plurality of axial passages 46 formed in the cylindrical member terminate in axial alignment with the channel 43. The upper surface of the member 44 is dished so that it engages the lower surface of the fins. Member 44 is provided on its outer periphery with threads 47 that are adapted to engage similar threads formed on the inner surface of tube 25.

Each of the parts 38 and 44 of the distributor member is made of some suitable refractory material such as a mullite composition that is fine grained and capable of withstanding the temperature and the temperature changes that are encountered in the base of the cup 24. The parts of the distributor are formed of ceramic moldings which can be assembled in various fashions. The head and stem, for example, are formed in accordance with conventional ceramic practice by the use of a suitably shaped die. The piece is then permitted to dry to increase its green strength prior to firing. Cylindrical member 44 is formed in the same manner.

As noted above, the parts 38 and 44 can be assembled in various fashions. These parts can be separately fired and joined together by a suitable cement. The parts may also be shaped and permitted to dry, then cemented together before being fired. In the latter event, there is a substantially one-piece instead of a two-piece construction. Another manner of making the distributor is to permit the head to dry for a short period of time during which a slight shrinkage will take place. Cylindrical member 44 can then be molded with its central opening exactly the same diameter as the stem 39. This part can then be placed on the stem so that as it dries it will shrink into engagement with the stem. Thereafter, when the parts are fired together they form, in effect, a single ceramic piece.

In the operation of the burner a combustible mixture is supplied under suitable pressure through the tube 25 toward the burner cup. This mixture passes through the axial passages 46 of member 44 and into channel 43 formed in the head portion of the distributor. The mixture then passes through the slots 42 into the cup where it is burned in a plurality of flames. Normally the inclination of the slots 42 will be such that as the mixture burns the outer surface of the flame, which is the hottest part thereof, will sweep along the surface of the cup to heat the latter to incandescence. Radiant heat from the cup as well as the hot products of combustion are used to heat the work in the chamber of which the burner itself forms a portion of the wall.

As shown in the drawing, there are sixteen of the axial passages 46 and thirty-two of the slots 42. It will be apparent, however, that a greater or smaller number of slots and passages may be formed depending upon the size of the

burner as well as upon the capacity thereof. It is noted that the tube 25 and the distributor in the end thereof can be removed from the burner block 21 by loosening bolts 35 and moving the entire assembly to the left in Figure 1 of the drawing. When necessary the burner tips can be readily replaced by unscrewing them from the end of the tube. This is facilitated by the use of a kerf or other depression 48 in which a suitable tool can be inserted.

In Figure 4 there is shown a distributor that is substantially similar to that described above except that the fins 41a extend inwardly from the periphery of the head to the stem 39. In this case an outer cylindrical member 51 is provided with internal threads 52 by means of which it is held in place on the stem 39. It is also provided with external threads 53 for attachment to the tube 25. This embodiment of the invention, however, differs mainly from that disclosed in Figure 2 in that the axial openings 54 are terminated in an annular channel or passage 55 slightly below the upper end of the cylindrical member. Thus it will be seen that the distributing channel 55 is formed in the cylindrical member 51 below the fins 41a instead of being formed in the head member 38 radially inward of the fins. Whether or not the construction shown in Figure 2 or in Figure 4 is used appears to be more a matter of choice than any inherent advantage which appears in one construction over that of the other.

The distributor that has been described above may be used in burners of any size. It is preferred, however, that those distributors described be used in burners of relatively small size, while burners having distributors of a size of 3 inches or more in diameter are preferably formed in a manner to be described.

A burner of the large size is shown in Figures 5 and 6. This burner comprises a cylindrical head 56 that is substantially frustoconical in shape. This head is provided with downwardly extending fins 57 similar to the fins 41 described in connection with the distributor of Figure 2. As is best shown in Figure 6 of the drawing, the outer edges of the fins are narrowed so that the slots 58 formed between the fins increase in width adjacent to the periphery of the head. Engaging the lower surface of the fins and the head 56, and in axial alignment therewith is a cylindrical member 61 having threads 62 on its outer surface. This member is provided with a plurality of axially extending passages 63 through which the combustible mixture flows to the channel 59 and to the slots 58. As is best seen in Figure 6, the passages 63 in this case are elongated instead of being circular, as was the case in the previously described embodiments of the invention. Such a construction increases the port area through which the combustible mixture flows and thereby increases the capacity of the burner.

Head 56 and the member 61 are held in assembled relation, shown in Figure 5, by means of a pin 64 having a head 65 on the lower end thereof. This pin is of a diameter to be received snugly in the central axial opening of the head and the cylindrical member. There is provided a cap 66 whose lower face is shaped to be received by the head 56, which cap is provided with threads 67 engaging similar threads on the end of the pin. The parts 61 and 56 are placed on the stem and the cap 66 is then tightly in engagement with each other. The

various contacting surfaces of the parts forming the distributor may be cemented together during assembly one either before or after firing in order to form, in effect, a one-piece distributor.

When burners of the type under discussion are used with a slow burning fuel such as natural gas, for example, it is desirable to provide some means to reduce the velocity of the gas as it is flowing into the cup and immediately prior to ignition. This can be accomplished by shaping the outer ends of the fins 51 in the manner shown in Figure 6 of the drawing. The enlargement of the slots 58 at the discharge end thereof will tend to decrease the velocity of the fuel as it is being discharged into the cup of the burner. This reduced velocity of the fuel gives more time for ignition thereof to take place and consequently the combustion is better. It is noted that fins 41 of the distributor described in Figures 2 and 3 may be shaped so that the slots 42 between them are flaring as are slots 58, if desired.

The distributor shown in Figure 7 is substantially identical with that described in Figures 5 and 6 except that the cap 66 and the head 56 of the embodiment of Figure 5 have been combined to form a single head member 68. This construction reduces by one the number of parts which must be molded in order to manufacture the distributor. Under ordinary circumstances the distributor shown in Figure 7 is the equal in all respects of that shown in Figure 5. In some critical installations, however, it may be necessary to line up the openings 63 with respect to the slots 58 in order to insure absolute equal distribution of the combustible mixture through the slots. When this is done the four-piece construction of Figure 5 is better since parts 56 and 61 can be properly aligned and retained in their aligned position while they are being fastened together by the holding means provided. The annular channel 55 may be made in part 61 instead of in part 56 in both this form of the invention and that of Figures 5 and 6, if desired. The fins 57 would then be elongated similar to the fins 41a of Figure 4.

Each of the embodiments of the invention has a head member including fins between which are formed slots that the fuel flows through, and a cylindrical member having axial passages through which the fuel flows on its way to the slots. It will be apparent that the parts of any one of the embodiments may be assembled in any of the ways mentioned depending upon the manufacturing facilities of the maker of burners of this type.

The distributor to which this invention is more particularly directed, and this distributor when used in combination with a burner block having a ceramic cup, permits the increase in capacity of a burner over the capacity of similar size burners using distributors of the type now generally in use. This is due to the increased port area that can be obtained with the construction disclosed herein. In addition to the above, the various parts forming the distributor of the present invention can be manufactured with the use of relatively simple dies and even though a plurality of parts is used, the cost of the dies and the assembling of the parts to form the distributor as a whole are less expensive than the dies and the molding of distributors now in use.

While in accordance with the provisions of the Statutes, I have illustrated and described the best form of embodiment of my invention now

known to me it will be apparent to those skilled in the art that changes may be made in the form of the apparatus disclosed without departing from the spirit and scope of the invention, as set forth in the appended claims, and that in some cases certain features of my invention may be used to advantage without a corresponding use of other features.

What is claimed is:

1. A distributor for use in a fluid fuel burner comprising a cylindrical head portion having a plurality of slots extending radially inward from the periphery thereof, a part of each slot being surrounded by the material of said head portion, a substantially cylindrical stem portion extending axially from said head portion and having a plurality of passages surrounded by the material of said stem portion, said passages extending axially from an end of said stem portion to a point adjacent to the inner end of said slots, and one of said stem or head portions being provided with an annular channel connecting with each of said slots and each of said passages whereby fuel can flow through said passages to said channel and out of said slots.

2. A distributor for a fluid fuel burner of the type in which there is provided a substantially cup shaped depression having a fuel supply opening in the base of the cup in which the distributor is received, said distributor comprising a block of refractory material substantially cylindrical in shape and having one diameter at a first end and a smaller diameter at a second end, the periphery of the first end being provided with a plurality of radially extending slots, a part of each slot being surrounded by the material of said block, said block having an annular passage formed therein communicating with the inner end of each of said slots, the smaller diameter of said block being formed with a plurality of axial passages surrounded by the material of said block, said passages extending from said second end to said annular passage, and a thread extending around the surface of said smaller diameter portion of said block by which the distributor may be threaded into the opening at the base of the cup of the burner.

3. A distributor for use in fluid fuel burners comprising a head having a cylindrical surface, said surface being formed with a plurality of slots extending radially inward therefrom, a part of each slot being surrounded by the material of said head, means forming an annular channel communicating with the inner ends of said slots, a cylindrical portion extending axially away from said head, said portion being provided with a plurality of passages surrounded by the material of said portion, said passages extending axially from the end thereof into communication with said channel.

4. The combination of claim 3 in which said axially extending portion is provided with continuous threads on its outer surface by means of which said distributor can be fastened into place in a threaded support.

5. A distributor for a fluid fuel burner comprising a cylindrical head portion having an axially disposed stem projecting from one side thereof, said head having in its periphery a plurality of slots extending radially inward and being formed around said stem with a channel communicating with the inner ends of said slots, a sleeve member received on said stem, said sleeve member having a plurality of axially extending passages therein which terminate in communication with said channel.

6. A distributor to be used in fluid fuel burners for subdividing the fuel into a plurality of streams comprising a substantially circular head portion having a peripheral surface and a stem projecting axially from one face thereof, a plurality of fins extending substantially perpendicularly from said surface and in the direction of said stem, said fins being separated from said stem to form a channel between the fins and stem, a member received by said stem and engaging the ends of said fins, said member being provided with passages extending therethrough into communication with said channel, whereby fuel can flow through said passages to said channel and can exhaust in a plurality of streams between said fins.

7. A distributor for fluid fuel burners comprising a substantially cylindrical body having a stem projecting axially from one face thereof, said body being formed with a plurality of radial grooves on said one face extending from the periphery thereof to said stem, an annular member received by said stem and having an end thereof engaging said one face, said member being provided with a plurality of passages extending therethrough in an axial direction, and said member being provided on said end with an annular channel communicating with each of said passages.

8. A distributor for fluid fuel burners comprising an annular member having opposed ends, one of said ends being formed with a plurality of substantially radial slots extending from the periphery thereof toward the center, and being provided with an annular channel communicating with the inner ends of said slots, second annular member to engage the said one end of said first annular member, said second annular member being provided with a plurality of axially extending passages communicating with said channel, and means having a part thereof extending through said annular members to hold the same in assembled relation.

9. The combination of claim 8 in which said second annular member is of smaller diameter than said first annular member and is provided with threads on its periphery.

10. A distributor for use with fluid fuel burners comprising a first annular member having opposed faces, a sleeve extending axially from one face thereof, a plurality of substantially radial fins extending from said one face of said member and extending inwardly from the periphery of said member to a point spaced from said sleeve, a second annular member having opposite ends and provided with axial passages spaced radially thereof from the axis so that they terminate in the space between said sleeve and the inner ends of said fins, one end of said second member being shaped to abut said fins and sleeve, and means having a portion thereof extending through said annular members to hold them in assembled relation.
